UNITED STATES PATENT OFFICE.

JAMES A. EVERITT, OF INDIANAPOLIS, INDIANA.

DESIGN FOR AN ATOMIZER-BODY.

SPECIFICATION forming part of Design No. 28,643, dated May 17, 1898.

Application filed November 6, 1897. Serial No. 657,705. Term of patent 7 years.

To all whom it may concern:

Be it known that I, JAMES A. EVERITT, a citizen of the United States, residing at Indianapolis, in the county of Marion and State 5 of Indiana, have invented a certain new Design for Atomizer-Bodies, of which the following is a specification.

Figure 1 of the drawings is a view in side elevation of an atomizer-body, showing my 10 new design. Fig. 2 is a cross-section of the body on the dotted line 2 2 of Fig. 1; and Fig. 3 is a cross-section on the line 3 3 of same figure, looking in the direction of the arrows.

The leading and material feature of my design 15 consists of a hollow cylindrical body A, which passes into a tapering or conical end

portion B, one side of the said tapering end portion being in the same plane with the corresponding wall of the cylindrical portion.

Having described my invention, what I 20 claim as new, and wish to secure by Letters Patent, is—

The design for an atomizer-body substantially as herein shown and described.

In witness whereof I have hereunto set my 25 hand and seal, at Indianapolis, Indiana, this 29th day of October, A. D. 1897.

JAMES A. EVERITT. [L. S.]

Witnesses:

JOSEPH A. MINTURN,
CARL SCHLEGEL.
